UNITED STATES PATENT OFFICE.

ANGELO JOSLER, OF CHICAGO, ILLINOIS, ASSIGNOR OF ONE-HALF TO FRANKLIN P. SMITH, OF CHICAGO, ILLINOIS.

WINDOW-GUARD.

1,178,925.

Specification of Letters Patent.

Patented Apr. 11, 1916.

Application filed January 8, 1915. Serial No. 1,081.

To all whom it may concern:

Be it known that I, ANGELO JOSLER, a citizen of the United States, and a resident of Chicago, county of Cook, and State of Illinois, have invented certain new and useful Improvements in Window-Guards, of which the following is declared to be a full, clear, and exact description.

This invention relates to window guards, 10 and one of its objects is to provide a window guard of improved construction capable of being readily installed in place in front of a window, and which is adjustable in width so as to accommodate windows of various 15 sizes.

Another object is to provide a guard which may be quickly and easily attached to or detached from its supports.

Another object is to provide a window 20 guard which does not interfere with, nor hinder the free movement of the window sash, but is positively locked in place by the sash whenever the latter is in a raised position.

25 Another object is to provide a window guard with locking means for locking the lower sash when fully lowered, and for locking the guard in place when the sash is raised or partly raised.

30 Another object is to provide a window guard capable of being collapsed so as to take up little room when not in use.

With these and other objects and advantages in view, this invention consists in the 35 several novel features of construction, arrangement and combination of parts hereinafter fully described and particularly pointed out in the claims.

The invention is clearly illustrated in the 40 accompanying drawings, in which:—

Figure 1 is a front elevation of a portion of a window, showing a simple form of window guard embodying the present invention, secured in place in front of the lower sash 45 of said window; Fig. 2 is a horizontal section taken on the line 2—2 of Fig. 1; Fig. 3 is a vertical section taken on the line 3—3 of Fig. 1; Fig. 4 is a perspective view of the locking mechanism and a fragment of the 50 window; Fig. 5 is a detail vertical section taken on the line 5—5 of Fig. 2; Fig. 6 is a detail horizontal section taken on the line 6—6 of Fig. 5; Fig. 7 is a detail horizontal section through the guard proper, taken on

the line 7—7 of Fig. 1; Fig. 8 is a front view 55 of a fragment of two intersecting upright and horizontal members of the guard proper; Fig. 9 is a front view of the guard proper collapsed; Fig. 10 is a perspective view showing the connection between a supporting member and the guard proper; Fig. 11 is a perspective view of a modified form 60 of the locking mechanism; Fig. 12 is a horizontal section taken on the line 12—12 of Fig. 11; Fig. 13 is a side elevation of a 65 second modified form of locking mechanism; and Fig. 14 is a plan thereof.

Referring to said drawings, and first to Figs. 1 to 10, inclusive, which illustrate the preferred embodiment of the invention, the 70 reference letter, A, designates the sill, B, B, the jambs of a window frame, and C, D, the upper and lower sash, slidably mounted 75 therein. Secured to the window stops, b, are two upright supporting members, 14, 75 for the window guard, here shown as formed of channel iron bars, extending from a point near the sill to one somewhat above the upper or meeting rail of the lower sash when fully lowered. Said supporting members, 80 14, may be secured to the window frame by screws, or otherwise, as desired. The guard proper is seen at E, and is removably secured to said upright supporting members, 85 14. In its preferred form, said guard proper comprises upright end members, 15, preferably formed of angle-iron bars for the purpose of obtaining strength, intermediate upright members, 16, and horizontal members, 17, extending between the upright end members, 15, and connected with 90 said upright end members and intermediate members to form a strong, substantial and rigid open work frame or grille work or grating. The horizontal members, 17, of 95 said guard proper are suitably spaced apart, to prevent the passage of a person between them, and the upright, intermediate members, 16, are so spaced as to insure strength and rigidity of structure. To provide for 100 adjustment for windows of different widths, the guard proper is made of two sections, slidably connected with each other, and as shown, each horizontal member comprises a tube and a rod sliding therein, but the horizontal members may comprise angle-iron bars, channel bars, or the like, the one being 105 slidably connected with the other, and the

one secured to the other in such manner that it cannot be disconnected from the other. In its preferred form, each horizontal member, 17, comprises a rod, 17^a, telescoping into a tube, 17^b. The horizontal members, 17, are secured to the upright members by lugs, 18, 18^a, 18^b, and in the preferred arrangement said lugs are swiveled on the upright members so that they may turn thereon. As shown, each lug is provided with a reduced round neck, 19 (see Figs. 7 and 8), seated in a round hole in the upright member, its end being headed down upon the outer face of the upright member. The outer ends of the horizontal members, 17, are rigidly secured in the end lugs, 18, as, for instance, by means of pins, 20, and the other ends of the tubular members, 17^b, are rigidly fastened in the lugs, 18^a, but the tubes slide through the lugs, 18^a, which are intermediate the ends of the tubes, and said intermediate lugs also form supports on the upright member, 16, for the tubes and rods contained therein. Preferably, the tubes on each end upright have rods interposed between them, as seen in Fig. 1, so that the lugs on each intermediate upright are rigidly fastened to the alternate tubes, the intermediate tubes sliding through the other lugs. The lugs, 18^b, have set screws, 21, threaded therein and adapted to bear against the rod members, 17^a, for connecting the two sections of the guard proper and fixedly holding them in any position of adjustment with respect to each other. By reason of the swiveled connection between the upright and horizontal members of the guard proper, it can be collapsed, as shown in Fig. 9, for the purpose of shipment or storage. Preferably, one or more of the lugs are provided with fingers, 18^c, projecting across an edge of the adjacent upright member, as shown in Figs. 1, 7 and 8, for the purpose of arresting relative movement between the upright and horizontal members when they are brought to a position at right angles to each other. This is simply a matter of convenience and facilitates the placing of the guard proper in position with respect to the locking mechanism.

The means for locking the guard proper to the window frame will now be described. Riveted, or otherwise fixedly secured to the lower ends of the upright supporting members, 14, are two brackets, 22 (see Fig. 10), each having a horizontal ear, 23, formed with a vertical aperture, for the reception of a stud pin, 24, which projects down from the horizontal ear, 25, of a bracket, 26, there being one bracket rigidly secured to the lower end of each upright end member, 15. When the guard proper is unlocked or unlatched from the upper locking devices, it may be detached from the brackets, 22, by

lifting it up until the pins, 24, are withdrawn from the holes in the horizontal ears, 23, of the brackets, 22.

The locking means for connecting the upper end of the guard proper with the window frame will now be described. Riveted or otherwise fixedly secured to the upper ends of the upright end members, 15, are two keepers, 27 (see Fig. 4), which are adapted for engagement with lock bolts or plungers, 28, that are movably mounted on the upright supporting members, 14. In the preferred form of the invention, said lock bolts or plungers, 28, are slidably, but non-rotatively mounted in horizontal ears, 29, 29^a, of brackets, 30, which are riveted or otherwise rigidly secured to the upper ends of the supporting bars, 14, and each lock bolt or plunger is here shown in the form of a square rod or bar sliding through square holes formed in said ears, 29, 29^a. A washer, 31, secured to the upper end of the lock bolt by the screw, 32, rests on the upper ear, 29, and supports the lock bolt or plunger. The keeper, 27, is provided with an opening, 33, which is adapted to receive the lock bolt or plunger when brought into register therewith, thereby locking the guard proper to the upright supporting members. Preferably, the lower end of the bolt, 28, is beveled off and the upper face of the keeper, 27, has a correspondingly beveled place for facilitating the lifting of the lock bolt when the guard proper is moved into locked position. Connected with said lock bolt, 28, is a slidable locking member, 34, which is capable of extending over the upper or meeting rail of the lower sash, thereby locking said sash down, and also capable of locking the lock bolt, 28, against movement relative to the latch member, 27. In the preferred form of construction, said locking member, 34, is in the form of a horizontally sliding bar, slidably mounted in the lock bolt, 28, near its lower end, whereby it may be pushed over the top of the upper or meeting rail of the lower sash or withdrawn therefrom, so as to lie adjacent the stile of the window sash. Means are provided between the bracket, 30, and lock bolt, 28, for preventing endwise movement of said bolt, and in the preferred form, the locking member, 34, is provided with an upwardly extending pin, 35, adapted to enter a hole, 36, in the lower ear, 29^a, of the bracket, 30, whenever the locking member, 34, is pushed over the top of the upper rail of the lower sash far enough to bring the pin, 35, and hole, 36, into register with each other. When, however, the locking member, 34, is retracted, and the pin is brought out of register with the opening, 36, its upper end engages with the lower face of said ear, 29^a, and prevents upward movement of the locking member, 34, and

lock bolt, 28; consequently, the lock bolt cannot be withdrawn from engagement with the keeper, 27, and therefore the guard proper cannot be removed until the locking member, 34, is shifted back over the sash to bring the pin into register with the hole in the ear, 29^a. Preferably, each locking member, 34, is provided with a shoulder, 37 (see Fig. 6) arranged to strike against the face of the lock bolt, 28, when the pin and hole are in register, and for convenience, a knob, 38, is provided on the extreme end of each locking member, 34, which may be grasped in manipulating it. Conveniently, the lower end of the bracket, 30, is formed with a horizontally extending guide member, 39, which has an outwardly curved, vertical edge for guiding the keeper, 27, when the guard proper is being put in place, and said bracket is also formed with a lug, 40, beyond said guide, 39, against which the keeper, 27, strikes whenever the lock bolt, 28, and opening, 33, of the keeper 27 are in register. To remove the guard proper, E, from its supports, the lower sash is first fully lowered, after which the locking members, 34, are pushed back over the top of said sash, thereby bringing the pins, 35, and holes, 36, into register. The guard proper, E, is then taken hold of and raised until the stud pins, 24, are withdrawn from the apertures in the ears, 23, after which the lower end of the guard proper is swung out slightly and then lowered to disengage the keepers, 27, from the lock bolts, 28. The guard may then be folded into the collapsed condition as shown in Fig. 9, and stored in some convenient place. The locking members, 34, now act as sash locks for the lower sash. To replace the guard proper, it is extended into open position, the stud pins, 24, inserted into the apertures of the ears, 23, and the upper end of the guard proper pushed back until the keepers, 27, engage the lock bolts, 28, and raise them, after which they drop into the apertures, 33, in said keepers. By drawing forward the locking members, 34, the guard proper is locked in place, and cannot be removed until the locking members, 34, are again pushed over the top of the lower sash. Whenever the lower sash is raised, or partly raised, its stiles lie in front of the heels of the locking members, 34, thereby preventing them from being pushed back, and whenever held in this forward position, the lock bolts, 28, are prevented from being raised because of the pins, 35, which strike against the lower faces of the ears 29^a.

In the modified form of locking mechanism shown in Figs. 11 and 12, the lock bolt, 28^a, is rotatively mounted in the ears of the bracket, 30^a, and the locking member, 34^a, is fixedly secured to said lock bolt near its lower end. As in the preferred construction, said locking member is provided

with an upstanding pin, 35^a, which, when brought into register with the aperture, 36^a, permits the locking member, 34^a, and lock bolt, 28^a, to be raised. By swinging the locking member into the position shown in dotted lines in Fig. 12, the pin, 35^a, is brought under the body of the ear, thus preventing the lock bolt from being raised.

In the modified form shown in Figs. 13 and 14, the lock bolt, 28^b, has a transversely extending pin, 35^b, secured to it, which engages with the under side of an ear or flange, 30^b, which projects out from the supporting member, 14^b, but which pin may be brought into register with a slot, 36^b, in said ear or flange, and the lock bolt may then be raised. A locking member, 34^b, here shown in the form of a pin extending through the lock bolt, 28^b, and fixedly secured therein, may be swung into the position shown in dotted lines in Fig. 14, thereby locking down the lower sash and bringing the pin, 35^b, into register with the slot, 36^b, for unlocking the guard from its supports, and said locking member, 34^b, may be brought into the position shown in solid lines, thereby bringing the pin, 35^b, out of register with the slot, 36^b, and preventing raising of the bolt, consequently locking the guard to its supports, as in the other forms.

It is perfectly evident from the above description that although the guard proper is positively locked in place, the lower sash may be freely raised and lowered, and that while in any raised position, the guard is positively locked in place, but when the sash is lowered to its lowermost position, the guard may be removed, but only at such time, and then only by moving the locking members across the upper rail of the lower sash, thereby locking it down, so that it is impossible to remove the guard proper from the outside, without breaking the glass, or some other portion of the structure.

The screws, 14^a, which fasten the supporting members, 14, to the window stops cannot be unscrewed because their heads are covered by the keepers, 27, and brackets, 25, while the guard proper is in place; consequently, the device cannot be removed as a whole, while the guard is locked in place.

The window guard may be readily installed, and no special tools are required for fastening it in place, and the wood trim is not necessarily marred, except for the screw-holes which receive the screws that fasten the supporting members in place.

The guard proper may be readily adjusted in width to accommodate various sizes of windows, the intermediate uprights, 16, being brought closer to each other as the guard is made wider, and farther apart as it is made narrower, but always preserving a symmetrical appearance for the guard.

More or less variation of the exact details

of construction is possible without departing from the spirit of this invention, and I desire, therefore, not to limit myself to the exact form of construction shown and described, but intend in the following claims to point out all of the invention disclosed herein.

I claim as new and desire to secure by Letters Patent:

10. 1. In combination, upper and lower connecting members adapted to be secured to the window frame of a window, a guard having means for detachably connecting it with said connecting members, and locking mechanism between the upper connecting members and guard, having a locking member adapted to project over the lower sash of the window when in unlocked position, and to lie in front of said sash when raised 20 from its lowermost position, and thereby lock said guard against removal.
2. In combination, upper and lower brackets adapted to be secured to the window frame of a window, a guard having means 25 for detachable engagement with said brackets, and locking mechanism between the upper brackets and said guard, having a locking member for locking the guard against removal when the lower sash of the window 30 frame is raised from its lowermost position, and arranged to unlock the guard from the upper brackets when moved over the top of the lower sash.
3. In combination, upper and lower brackets 35 adapted to be secured to the window frame of a window, lock bolts movably mounted in the upper brackets, locking members, one connected with each lock bolt and having means arranged for engagement 40 with its associated bracket to prevent upward movement of the lock bolt, except when pushed over the top of the lower sash of the window, and a guard having means for detachably connecting it with the lower 45 brackets, and keepers arranged for locking engagement with said lock bolts.
4. In combination, upper and lower brackets arranged to be secured to the window frame of a window, lock bolts mounted to 50 slide vertically in said upper brackets, locking members carried by said lock bolts and arranged to extend over the top of the lower sash of the window and to be withdrawn therefrom to lie in front of the stiles thereof, and a guard having means for detachably connecting it with the lower brackets and keepers arranged for locking engagement with said lock bolts.
5. In a window guard, locking mechanism 60 comprising a bracket adapted to be secured to the window frame of a window, a lock bolt slidably mounted in said bracket to move in a vertical direction, a locking member carried by said bolt and arranged to be 65 moved across the top of the lower sash of

the window to lock the same in its lowermost position, and also arranged to be withdrawn from said position to lie in front of the stile of said sash, means for preventing upward movement of said lock bolt when said locking member is retracted, and a keeper arranged to be carried by a guard and adapted for locking engagement with said lock bolt. 70

6. In a window guard, the combination of a lower bracket arranged to be secured to the window frame of a window and having a vertical aperture, a guard having a downwardly projecting pin arranged to enter said aperture, an upper bracket having a vertically sliding lock bolt mounted 80 therein, a keeper arranged to be carried by the upper end of said guard and arranged for locking engagement with said lock bolt, and a locking member carried by said lock bolt and having means for preventing upward movement of said lock bolt when in a position lying in front of the stile of the lower sash, but capable of being moved over the top of said lower sash to permit vertical movement of said lock bolt. 85

7. In a window guard, the combination of a bracket adapted to be secured to the window frame of a window, a lock bolt movably mounted therein, a locking member capable of being moved over the top 95 of the lower sash to lock the same down, and also capable of being retracted to extend in front of a stile thereof, said locking member having means for engaging said bolt and preventing upward movement thereof when in one position, and a guard having a keeper arranged for locking engagement with said lock bolt. 100

8. In a window guard, the combination of a bracket arranged to be secured to the window frame of a window, a lock bolt mounted in said bracket to slide in a vertical direction and secured therein against rotation, a locking member slidably mounted in said lock bolt and having a portion adapted to extend over the top of the lower sash of said window when in one position, but capable of being retracted therefrom to lie in front of a stile of said sash, said locking member having an upstanding pin arranged to strike against said bracket when the locking member is retracted from a position over the lower sash and thereby prevent upward movement of the locking member and lock bolt, and a guard having a keeper arranged for locking engagement with said lock bolt. 115

9. In a window guard, the combination of a bracket adapted to be secured to the window frame of a window, and having two horizontally extending ears, a lock bolt non-rotatively mounted in said ears and having a limited amount of vertical movement, a locking member carried by said lock bolt and having a portion capable of being 125 130

- 5 moved across the top of the lower sash of the window, and also capable of being retracted therefrom to lie in front of a stile thereof, said locking member having an up-
 10 standing pin arranged to strike against one of the ears of said bracket when retracted, and adapted to be brought into register with an aperture in said ear when moved across the top of the lower sash, whereby
 15 said locking member and lock bolt may be raised, and a guard having a keeper arranged for locking engagement with said lock bolt.
10. In combination, lower guard securing
 15 means adapted to be supported by the window frame of a window, a guard having means for detachably connecting it with said securing means in front of the lower sash, and upper guard securing means hav-
 20 ing a guard engaging member supported on the window frame and having an element adapted to project over the lower sash of the window when in unlocked position, and to lie in front of said sash when it is raised
 25 from its lowermost position, and thereby secure the guard engaging member against movement relative to the guard, and there-
 with to lock the guard against removal.
- 30 11. In a window guard, a guard proper comprising upright end members adapted to be detachably secured and locked to the window frame of a window, upper and lower horizontal telescoping members, intermediate horizontal telescoping members secured to said upright end members, and intermediate upright members having lugs swiveled thereon, certain of said lugs being secured to the ends of the tubular portions of the telescoping members, and the other
- 40 lugs being slidably connected with said tubular portions of the telescoping mem-
 bers.
- 45 12. In a window guard, a guard proper, comprising upright end members adapted to be detachably secured to the window frame of a window, horizontal tubular members and rod members pivotally secured to each upright end member, the rod members and tubular members of each upright end member being arranged alternately, and the rod members of each upright end member telescoping into the tubular members, intermediate upright members, lugs swiveled to said upright members, certain of said lugs being secured to the inner ends of the tubular members, and the other lugs being slidably mounted on said tubular members intermediate their ends.
- 50 55 13. In a window guard, a guard proper, comprising upright end members adapted to be detachably secured to the window frame of a window, horizontal tubular members and rod members secured to each up-
 60 right end member, the rod members and tubular members of each upright end mem-
 ber being arranged alternately, and the rod members of each upright end member tele-
 65 scoping into the tubular members, intermediate upright members, lugs secured to said upright members, certain of said lugs being secured to the inner ends of the tubular members, and the other lugs being slidably mounted on said tubular members intermediate their ends.

ANGELO JOSLER.
